(57) **CLAIM**

We claim the ornamental design for a pneumatic gripper apparatus for handling goods, as shown and described.

DESCRIPTION

FIG. 1 is a front view of a pneumatic gripper apparatus for handling goods showing our new design;

FIG. 2 is a back view thereof;

FIG. 3 is a top view thereof;

FIG. 4 is a bottom view thereof;

FIG. 5 is a perspective view thereof;

FIG. 6 is a right side view thereof; and,

FIG. 7 is a left side view thereof.

The broken lines in the drawings depict portions of the pneumatic gripper apparatus for handling goods that form no part of the claimed design.
